UNITED STATES PATENT OFFICE.

WILLIAM W. GRISCOM, OF HAVERFORD, PENNSYLVANIA; DORA INGHAM
HALE GRISCOM EXECUTRIX OF SAID WILLIAM W. GRISCOM, DECEASED.

MANUFACTURE OF STORAGE-BATTERY GRIDS.

SPECIFICATION forming part of Letters Patent No. 597,846, dated January 25, 1898.

Application filed November 22, 1895. Serial No. 569,850. (No model.)

To all whom it may concern:

Be it known that I, WILLIAM W. GRISCOM, a citizen of the United States, residing at Haverford, in the county of Montgomery and 5 State of Pennsylvania, have invented certain new and useful Improvements in the Manufacture of Storage-Battery Grids, of which the following is a specification, reference being had therein to the accompanying drawing.

10 My invention relates to machines for casting storage-battery grids, and has for its object to improve the construction of such machines and to provide means whereby grids may be cheaply and rapidly made and where- 15 by grids of complicated form may be more perfectly cast; and to these ends my invention consists in the novel arrangement, construction, and combination of parts herein- 20 after more particularly described.

25 While the invention is intended more particularly to be used in making storage-battery grids from lead, it is evident that it can be used for making other and different articles from other and different materials and may 30 with proper modifications be applied whenever it is desirable to make difficult castings for any purpose whatever.

35 In the accompanying drawing, forming a part of this specification, the figure is a longitudinal section of a machine made in accordance with my invention, parts being in side elevation.

40 The pots or ladles 11 are suspended from opposite ends of a walking-beam 2 and are connected to said beam by means of chains or rods secured to blocks 16, adapted to move in slots 15 of the beam 2 to accommodate the varying positions of the ladles. An oscillating movement may be imparted to the walking- 45 beam 2 by means of cords 13, connected to opposite ends of the beam and passing over suitably-arranged pulleys to a point within easy reach of the operator. Each ladle is inclosed within a casing 4 of such diameter

50 as to leave a space between the two, and the ladle is heated by means of a burner 3, supported within the casing beneath the ladle and communicating with a flexible supply pipe 14.

55 The ladles 1 are provided with outlet-openings controlled by means of valves 6, and

these openings communicate with openings 7^b in the chill-frame 7 through pipes 5, which are joined to the chill-frame in such manner as will permit them to be moved vertically. 55

Within the chill-frame is fixed the lower half 8 of the chill, forming, in connection with the sides of the frame, a tight box or receptacle, the openings in the chill-frame leading from said receptacle from opposite sides 60 thereof and at points immediately above the top of the lower half of the chill.

The upper half of the chill fits closely the space between the sides of an auxiliary chill-frame 7^a, the sides of which register with those 65 of the main chill-frame 7 when the halves of the chill are together, and this auxiliary frame is hinged to one side of the main frame at 10.

The sides of the main chill-frame project above the top of the lower half of the chill, 70 forming a surrounding flange, and when the upper half of the chill is in engagement with the lower half its edges are in engagement both with the sides or flange of the main frame and those of the auxiliary frame, and 75 by reason of this the auxiliary frame cannot be swung upon its hinge until the upper chill-section is moved vertically out of engagement with the sides of the main frame, when the said section and frame may be swung rear- 80 wardly in the arc of a circle to permit the lower chill-section to be readily accessible. It will be noted, too, that when the upper chill-section is in position upon the lower section its edges serve to close the openings 85 7^b on the main chill-frame, said openings being gradually closed as the upper chill-section descends.

90 In order to effect the vertical movement of the upper chill-section, a centrally-slotted lever 11 is pivoted upon the frame 7^a, and into the slot of this lever projects a stud 17 from the upper chill-section. From this it will be obvious that when the chill-section is in its lowermost position the stud will be at one end 95 of the slot in the lever 11, and as said chill-section is lifted vertically the position of the stud in the slot constantly changes until it is brought into contact with the opposite end of the slot, such contact taking place when the 100 chill-section is above the sides of the main frame 7, and by reason of this contact the

chill-section becomes locked against any further movement in the frame 7^a, and the further movement of the lever will cause the frame 7^a to swing upon its pivot, carrying the 5 chill-section 9 with it, to a vertical or substantially vertical position.

It is sometimes desirable to vary the thickness of castings, and to accomplish this I provide means for adjusting the upper chill-section nearer to or farther from the lower section, such means consisting of guides 7^c upon the front edge of the frame 7^a, having a vertical series of openings for reception of a pin, the said pin serving as a bearing for the lever 10 11 when it is in its lowered position. From this it will be apparent that if the pin be inserted into the lowermost opening of the series the upper chill-section will be permitted to approach the lower section nearer than if 15 20 the pin were inserted into any other opening of the series.

While the lower chill-section is shown and described as formed separately from and connected to the chill-frame and the sides of the 25 said frame surrounding and extending above the chill-section to form a flange, it will be understood, of course, that the surrounding flange may be formed integral with the mold-section and the opening 7^b extended through 30 such flange.

In their normal positions the ladles are each below the plane of chill-section 8, and while in this position metal cannot be introduced into the chill. In the operation of casting, 35 however, the walking-beam is canted, which has the effect of elevating one of the ladles above the level of the chill and simultaneously lowering the other ladle. The metal then runs into the receptacle formed by the 40 sides of the main frame and the lower chill-section, completely filling the recesses in the latter. After this the auxiliary chill-frame is swung into position upon the main frame, and the upper chill-section is then lowered by 45 means of the lever 11, and in its descent it forces all surplus metal through one of the openings 7^b into the lowest ladle. When the upper chill-section is in position, its edges close both the openings 7^b and prevent both 50 55 the supply and discharge of the metal to and from the chill.

What I claim is—

1. In a sectional mold, the combination with one section having a surrounding flange 55 extending beyond its face, of a second section adapted to be received between the flange of the first section, means for moving the second mold-section toward and away from the first

section, and a receptacle below the plane of the mold, communicating with the interior 60 thereof for reception of the superfluous metal, substantially as described.

2. In a molding-machine, the combination with a stationary chill or mold, of a ladle and connections between the mold and ladle, said 65 connections permitting the ladle to be moved above and below the plane of the mold, substantially as described.

3. In a molding-machine, the combination with the upper and lower sections of a chill 70 or mold, the lower section being surrounded by a frame which extends above it, of a ladle communicating with the interior of the mold through an opening in its surrounding frame, substantially as described.

4. In a molding-machine, the combination with the chill or mold, of a ladle, a pipe connecting the ladle with the mold, and a loose joint between the pipe and mold whereby the ladle and pipe may be moved with relation to 80 the mold, substantially as described.

5. In a molding-machine, the combination of the chill or mold formed in sections, one of which is stationary and the other movable, a main frame for supporting the stationary 85 chill-section, said frame partially inclosing and projecting above the stationary chill-section, an auxiliary frame hinged to the main frame at one side and adapted to contain the movable chill-section, and means for lifting 90 the said chill-section independently of the frame and for moving both simultaneously, substantially as described.

6. In a molding-machine, the combination with the upper and lower sections of a mold 95 or chill, the lower section being surrounded by a frame which extends above it, of a ladle and connections between the ladle and the interior of the mold, said connections permitting the ladle to be moved above and below 100 the plane of the mold, substantially as described.

7. The combination with the mold, of a ladle, a pipe connecting the mold and ladle and arranged to be moved through an arc of a circle independently of the mold and above and below the plane thereof, and means for heating the ladle, said means being arranged to move with the ladle, substantially as described.

In testimony whereof I affix my signature in presence of two witnesses.

WILLIAM W. GRISCOM.
